US00D608966S

(12) **United States Design Patent**
Chu

(10) **Patent No.:** **US D608,966 S**
(45) **Date of Patent:** **** Jan. 26, 2010**

(54) **WASTE RECEPTACLE**

(75) Inventor: **Frank Chu**, San Francisco, CA (US)

(73) Assignee: **Alternate Choice, LLC**, San Francisco, CA (US)

(**) Term: **14 Years**

(21) Appl. No.: **29/325,411**

(22) Filed: **Sep. 30, 2008**

(51) **LOC (9) Cl.** **09-09**

(52) **U.S. Cl.** **D34/1**

(58) **Field of Classification Search** **D34/1-11; 220/908-911**

See application file for complete search history.

(57) **CLAIM**

The ornamental design for a waste receptacle, as shown and described.

DESCRIPTION

FIG. 1 is a top perspective view of a waste receptacle; FIG. 2 is a front view of the waste receptacle shown in FIG. 1; FIG. 3 is a left side view of the waste receptacle shown in FIG. 1; FIG. 4 is a right side view of the waste receptacle shown in FIG. 1; FIG. 5 is a back side view of the waste receptacle shown in FIG. 1; FIG. 6 is a top view of the waste receptacle shown in FIG. 1; and, FIG. 7 is a bottom view of the waste receptacle shown in FIG. 1. The broken line showing of some features in the figures is included for the purpose of illustrating environment and forms no part of the claimed design.

1 Claim, 7 Drawing Sheets
